US0D1112630S

(12) **United States Design Patent** (10) **Patent No.:** **US D1,112,630 S**
(45) **Date of Patent:** **** Feb. 10, 2026**

(54) **FAUCET**

(71) Applicant: **GESSI S.P.A.**, Serravalle Sesia (IT)

(72) Inventor: **Gian Luca Gessi**, Serravalle Sesia (IT)

(73) Assignee: **GESSI S.P.A.**, Serravalle Sesia (IT)

(**) Term: **15 Years**

(21) Appl. No.: **29/992,658**

(22) Filed: **Mar. 10, 2025**
